UNITED STATES PATENT OFFICE.

LOUIS EGGER, OF SUMISWALD-GRUNEN, BERNE, SWITZERLAND.

BOOK-SEWING MACHINE.

Application filed December 21, 1921. Serial No. 523,989.

To all whom it may concern:

Be it known that I, LOUIS EGGER, a citizen of the Swiss Confederation, and residing at Sumiswald-Grunen, Berne, Switzerland, have invented certain new and useful Improvements in Book-Sewing Machines, (for which I have filed an application in Switzerland on December 18, 1920), of which the following is a specification.

10 The present invention has reference to improvements in book sewing machines of the type in which, in cooperation with a rocking work table and a reciprocating perforator, one or more sets of stitching needles, 15 each set comprising a hooked needle and an eyed needle, reciprocate vertically in timed relation with a thread layer transversely reciprocating between the needles, and the invention has for its object to generally improve the construction and operation of such 20 machines, mainly as relates to the guidance of the sewing thread and the operation of the work table, as will now be described in detail in connection with the accompanying 25 drawings, in which Fig. 1 is a front elevation of the machine, several parts being omitted for the sake of clearness; Fig. 2 is a side elevation, partly in section; Figs. 3, 4 and 5 illustrate the thread clamping device in front view, vertical section and detail 30 top view respectively; Fig. 6 is a fragmental front view of the middle part of the machine, of which Fig. 7 is a side elevation, partly in section; Fig. 8 is a front view of 35 a stitching head, and Fig. 9 is a section therethrough; Fig. 10, finally, illustrates a detail of Fig. 8 in section.

As shown by way of example the machine is provided with only one set of stitching units, which includes an eyed needle and a hooked needle, for stitching the sheets at one place only, but it is to be understood that, for operating on wide sheets, two or more such stitching units may be provided.

40 The standards 1 and 2 journal the main driving shaft 3 to which is fixed between the standards a cam disc 4 presenting on its inner face two cam grooves 8 and 9, from which are respectively actuated the work table and the stitching heads with their needles, and on the left outside of standard 2 there is fixed on the shaft 3 a cam disc 50 with a cam groove 7 for actuating the perforator bar. Of these cam curves there 55 are shown in Fig. 2 only the inner circumferential edges in dotted outline. To the hub

of cam disc 5 there is fixed the cam drum 6, provided on its circumference with the substantially parallelly directed, intercrossing cam grooves 61 and 62, which serve to displace the eye needles, as later on fully described.

The work table comprises the two leaves 10 and 11 which are laterally supported by the lever legs 12 and 13 fixedly extending from the rock shaft 14 journaled in the standards 1 and 2. This rocking table is actuated by the link 15 whose upper end is fixed on the rock shaft 14 and whose lower end, provided with a roller 16, is guided in the cam groove 8 of disc 4. On the rocking table is mounted the thread layer 18 and also the perforator bar. The hooked thread layer 18 is secured to a horizontal rod 17 which can be reciprocated longitudinally in the two table legs 12 and 13 by means of a bell crank 20 pivoted on a frame bracket 19 and a link member 21 (Fig. 1) adapted to be vertically reciprocated in any suitable manner, not specially shown here. From the left end of the shiftable rod 17 rigidly depends a slide arm 22 and a spring 23 which latter, on the lateral displacement of the rod 17, contactingly slides on the guide rail 24 fixed on the table leg 13.

The perforator bar 64 carries the piercing or punching members 25 and reciprocates vertically on the guide checks 26 and 26', and it is actuated by the link rods 28 and 28' which are pivoted below to the levers 31 and 31' fixed to a shaft 30 which is journaled in the table legs 12 and 13 parallel to the rock shaft 14. To the shaft 30 is further secured a three-arm lever 33 to the lower end of which is pivoted the one end of a connecting rod 34, whose other end is fixed to a cross-head 35 supporting a roller 36 which latter extends into and is actuated by the cam groove 7, the side members 37 and 37' being guided in a cross-member 38 loosely riding on shaft 3.

To the upper end of this triple lever 33 is secured a screw bolt 39, adapted to press against the slide arm 22 (Fig. 7) when the latter assumes its outermost operative position and rotates the thread layer. The third arm 67 of the triple lever 33 serves for locking the work table.

The table locking mechanism comprises a slide 69 presenting above a hook nose or latch 68, which slide is reciprocably mounted by guide bolts 71 and 71' on the standard 2

and is influenced by the draw spring 70, said bolts passing through slots 69' in the slide. Obviously, such a latch slide may be provided also on the other standard 1.

5 In the longitudinally slotted cross-head 40, up and down reciprocable on the lateral guide cheeks 41 and 41', is mounted a bar 42 with capability of longitudinal displacement. On this bar is fixed a stitching head 43 supporting the eyed needle 43' whilst a stitching head 45, supporting a hooked needle 45' at the lower end of the needle carrier 59 and a pinion 44 at the upper end, is mounted on the cross-head 40. The latter is actuated 10 by means of the connecting rods 46 and 46' pivoted to the bell cranks 48 and 49 fixed on the shaft 47, the ends of which latter are journaled in the standards 1 and 2. Below there is fixed in these standards a shaft 29 15 on which is rockingly mounted the two-arm lever 32, the outer end of which is connected by the rod 50 with the bell crank 49. The inner end of this lever 32 carries a roller 51 which engages in the cam groove 9 of the disc 4.

For making the zig-zag stitch the bar 42 with its stitching head 43 is horizontally reciprocated from the grooved cam disc 6 by the intermediary of the double-armed 20 lever 54, rockingly journaled in the support bracket 53. The upper end of this lever 54 is pivoted to the outer end of a cross-rod 57 and its lower slide shoe end 52 alternately engages in the drum grooves 61 and 62.

25 To the horizontally displaceable rod 55 is fixed a fork member 56 which by means of the cross-rod 57 connects with the lever 54 and straddles a bolt 58, freely extending through the slotted cross-head 40 and fixed in the bar 42 (Fig. 2).

The hooked needle is rotated by means of the pinion 44 fixed on the needle carrier 59 in coaction with the stationary rack 60, the cross-head 40 being horizontally displaced 30 as by cam means, not shown. The stitching head 43 is provided with a longitudinal groove 72 (Fig. 10) in which the bar 74 carrying the eye-needle guide 73 can be reciprocated. From a crossbar 75 fixed on the standards 1 and 2 rigidly extends the needle plate 76, which on the one hand serves as counter-pressure member for the perforator and on the other hand has support for the hooked needle guide 77, and also as support 35 for the longitudinally grooved guide plate 78. From the bar 74 extends rearwardly a finger 79 which engages in a groove 78' in the guide plate 78 in such manner that on reciprocation of the eyed needle head and on transverse displacement thereof the relative position of the needle guide 73 will always remain the same.

Above the work table there is provided in the standards 1 and 2 a rock shaft 65 supporting the stripper-off 66, which latter serves

to press the last stitched sheet against the just previously stitched sheet. This stripper-off is actuated from the cam disc 80 (Fig. 1) by the intermediary of the cam-groove operated bell crank 81 and the connecting rod 82, which latter is pivoted on the lever arm 104 rigidly extending from the rock shaft 65.

Upon the cross-bar 83, connecting the standards 1 and 2, is mounted the thread clamping device. The bar 83 is provided with downwardly tapering bores 83', in which engage the truncated cone shaped plugs 84 (Figs. 3, 4 and 5). The bore walls are split at one side to present thread introducing passages 85. For each needle pair there is provided one such bore. From the top of each plug extends a guide pin 84' slidable in the guide bar 86, and a spring 87 tends to press the plug down into its seat. For operating this thread tensioning device there is provided in contact with the bottom faces of the plug or plugs a swing bar 88, which is acted on by screws 90 and 90' extending from arms 89 and 89', which latter form rigid parts of the stripper-off 66 (Fig. 2). The entire thread tension mechanism forms, as it were, an independent unit.

From the standards 1 and 2 rise respectively the supports 91 and 91' connected by a shelf 92, upon which are mounted the thread spools 93 and the bracket supports 94 and 94'. These latter are interconnected by two rods 95 and 96 which serve as thread guides.

From the shaft 97, rotatably mounted in the standards 1 and 2, rigidly extend the lever arms 98 and 98' to the outer ends of which are pivoted the draw rods 100 and 100', connected by the cross-rod 99, which supports a thread tensioning spring 101, the draw rods 100 and 100' being guided in the cross-bar 83. This thread tensioner is actuated by means of a cam disc, not shown here, by the intermediary of the draw-rod 103 and the lever arm 102 fixed on shaft 97.

The operation of the described mechanisms is the following: The sheet to be stitched is placed upon the work table, which is in the outer, dotted-line position in Fig. 2. After the table has been swung into the full-line position, the sheet is pre-pierced by the perforating needles. During the ascent of the latter the lever arm 67 swings down, causing the hook 68 of the slide 69 to latch into the slotted table leaf 11 (Fig. 7) which locks the work table, so that it cannot recede in the direction of the arrow under the pressure exerted by the perforating operation. In the sewing of wide sheets, for instance for large ledgers and the like, a relatively large number of perforating needles are used, so that, especially with thick folds, quite a strong pressure has to be reckoned with, and for this reason it is advisable to securely lock the table. After the holes have

been punched the perforator 64 recedes and the lock slide 69 is moved up again by the arm 67 for releasing the table. Into the sheet perforations are now simultaneously introduced from above the threaded needle and the hook-needle with the hook of the latter pointing forward. During the descent of the needles the screws 90 and 90' bear against the swing bar 88 and cause the latter to lift the plug or plugs 84 for momentarily releasing the thread. The thread layer 18 now seizes the thread introduced by the eyed needle and carries it to the hooked needle, which latter meanwhile has passed through a half-revolution, and deposits it into the hook thereof. The screws 90 and 90' recede from the swing bar 88 and the plugs 84 are pressed down into their seats by the springs 87 for clamping the thread. The insertion of the thread and the rotation of the thread layer is brought about by the short cam surface 7' in the cam groove 7 (Fig. 2) whereby the lever 33 is rocked and causes the slide lever 22 to swing rearwardly which takes place after the rod 17 has completed its longitudinal displacement toward the hooked needle. On the ascent of the stitching needles the introduced thread is caught by the hooked needle and the caught loop is drawn through the loop of the previously stitched sheet which still surrounds the hook-needle, whereupon the latter is again turned through a half-revolution. During the latter part of the needle ascent the thread is drawn taut by the thread tensioning levers 98 and 98', so that a chain-stitch of close formation from sheet to sheet is obtained.

The thread is drawn off the supply spools by a thread drawing mechanism, well known in the art and for that reason not specially shown here. After the thread layer has returned into its initial position the table is swung back into its outer, dotted-line position (Fig. 2), the slide shoe 52 changing from the drum groove 61 over into groove 62, which shifts the eyed needle toward the left. Simultaneously the stripper-off 66 is swung down into the dotted-line position II in Fig. 2, presses the halves of the just stitched sheet together and at once returns into the full-line position. A fresh sheet is now placed upon the work table and the described operations are repeated, the slide shoe 52, in this instance, changing back again from the groove 62 into groove 61,

shifting back thereby the eyed needle from left to right, so that the eye-needle executes a stitch of zig-zag formation upon the back of the book.

60

What I claim is:

1. In a book sewing machine, a work table, means rockingly supporting the same, a perforator, means for latching the table in an operative position for perforating operation, and means operable by and during actuation of the perforator for rendering said second means operative.

65

2. In a book sewing machine, a movably supported work table, perforating means carried thereby, latch means for holding the table fixed during operation of said first means, and a common actuator for simultaneously rendering said perforating means and latch means operative.

70

3. In a book sewing machine, a laterally reciprocable stitching head, an eye-needle bar slidably mounted thereon, a stationary perforated needle plate carried by the head, a horizontal guide plate on said needle plate, and means carried by the bar and slidably engaged with the guide plate for permitting horizontal displacement of said needle guide with said needle bar.

75

4. In a book sewing machine, including a perforator and a rocking work table, means for locking said work table during the perforating operation, comprising a slide member, a spring-influenced latch extending therefrom, adapted to coact with said rocking work table in the operative position thereof, and cam operated means for disconnecting said latch and said work table immediately after the perforating operation.

80

5. In a book sewing machine, including a perforator and a laterally reciprocable stitching head presenting a longitudinal groove in its outer face, an eye-needle bar reciprocable in said groove, a stationary perforated needle plate, serving as counter-pressure member during the perforating operation and as guide for said eye-needle bar, a horizontally slotted guide plate on said needle plate, a finger inwardly extending from said needle bar, adapted to be guided in the slot of said guide plate, for the purpose of allowing horizontal displacement of said needle guide with said needle bar, but preventing it from following the latter's vertical displacement.

85

In testimony whereof I affix my signature.
LOUIS EGGER.
